UNITED STATES PATENT OFFICE

JOSEPH MAY, OF FRANKFORT-ON-THE-MAIN, GERMANY.

ARCH-SUPPORT FOR HOLLOW AND FLAT FEET.

1,172,620.

Specification of Letters Patent. Patented Feb. 22, 1916.

Application filed January 20, 1914. Serial No. 813,234.

To all whom it may concern:

Be it known that I, JOSEPH MAY, a subject of the Emperor of Germany, and a resident of Frankfort-on-the-Main, Germany, have invented certain new and useful Improvements in Arch-Supports for Hollow and Flat Feet, of which the following is a specification.

This invention relates to an interchangeable arch support for footwear for hollow and flat feet, which is adapted to be brought into and adjusted at various angular positions relatively to the center line of the foot.

The arch support itself may be of various types. It may be rigid, springy, adjustable or non-adjustable, and it may be provided with rigid or movable and exchangeable lateral extensions or even without such extensions.

The object of the invention is to provide a suitable interchangeable arch support for footwear which can be placed at different angles to the joint and to the static center line of the foot, thus enabling the arch support to be set correctly according to the degree of abduction of the heel and the inclination of the foot. This is attained in that the heel part of the arch support is rotatable and the ball part is provided with suitable adjusting means. According to the type of arch support, and according as to whether it is mounted on the cover or inner sole, the kind and arrangement of the means employed for permitting the turning and adjustment to be effected, may or must be varied.

The drawing illustrates some examples of construction according to this invention.

Figure 1 is an underneath plan view. Fig. 2 is a corresponding side view showing one example of construction with a single heel-turning point. Fig. 3 is an underneath plan of an example of construction having a number of heel-turning points. Figs. 4 and 5 show two different heel plates and their method of being fastened and Figs. 6 and 7 show in two sections at right angles a turning pin which may serve at the same time as the locking member.

In Figs. 1 and 2 the plate *a* is shown which in this case may have a spring action, and is provided with the usual exchangeable band or tie for varying its curvature arranged in the arch thereof. Its heel part is rotatably connected to the cover *c* of leather or other suitable material by a rivet

b or the like. Its ball part rests on a guide plate *d* which is so connected to the cover *c* that freedom of movement is provided for the ball-part of the spring plate *a*. On the ball-part of the spring plate is provided an adjusting- or guide-pin *e* and in the plate *d* are formed side by side a number of adjusting and guiding slots *f* therefor, which are preferably radial to the pivot pin *b* forming the turning point of the arch support, so that the pin *e* can slide in said slots *f* without turning movement, and the ball part of the arch support can move as far as is permitted by the length of the slots. By lifting the ball part of the arch support the adjusting and guiding pin *e* can be raised out of one of the slots *f* and inserted into another. During use, however, it cannot come out accidentally as the arch support supports the weight of the wearer and the pin *e* is therefore always pressed downward. By inserting the pin *e* into one or the other of the slots *f*, the angular position of the arch support can be varied to suit the abduction of the heel or the inclination of the foot.

In Fig. 1 of the drawing a different angular position is indicated by the dot and dash line.

In arch supports of which the ball part is not required to slide forward simple adjusting holes can be provided for the pin *e* in place of adjusting and guide slots *f*. It is also not essential that the holes or slots for the pin *e* should be in a separate plate, but they may be formed directly in the loosely-inserted or fixed inner sole.

For the purpose of increasing still further the possibility of adjustment of the foot-arch plate *a*, its angular turning or fixing pin *b* may also be made adjustable in the sole. This permits of varying the position of the foot-arch plate itself between the inner sole and the cover both laterally and longitudinally, and also permits of greater angular adjustment. Moreover in this case the foot-arch plate is only removably connected to its cover or the inner sole so that it can easily be exchanged and another can be inserted between the cover and inner sole. An under-side plan of such an example of construction is shown in Fig. 3. According to this arrangement the arch-plate *a* is provided with a turning pin *b* at the heel part as in the construction first described. For the reception of this pin, a number of holes are provided in suitable

positions in the inner sole or cover. The positions of these holes are so chosen that the turning pin *b*, by being engaged in one or other of the holes, will carry the arch-plate more to the right or to the left of the longitudinal center line of the sole, or more to the front or to the rear. Different positions of the arch plate proper relatively to its cover and also to the sole are shown in Fig. 3 by full lines, simple dashed lines and dot-and-dash lines.

Instead of stamping the holes for the turning pin *b* directly in the sole or the cover, a separate bearing plate *g* can be riveted or otherwise fixed to this as shown in the drawing. The bearing plate *g* may also be secured to separate heel and supports, or may even be formed as such an arch support or it may retain such an arch support between itself and the inner sole or the cover.

In the example of construction shown in Fig. 4 the bearing plate is stamped out of the heel plate in the form of a tongue, and the arch-plate slides with the end of its heel-part between the plate and the tongue.

The turning pin *b* may advantageously have its head bent backwardly, or made elongated in form, while the holes are of similar form transversely, so that after being inserted in a hole, the head of the pin can be turned across the same, when it cannot come out accidentally. Fig. 3 shows this in plan, and Figs. 6 and 7 show it in two sections at right angles. The position of the pin is preferably such that its free sharp lower end projects somewhat beneath the bearing plate *g*, so that it will engage with the sole when the arch support supports the weight of the wearer, or will be pressed into this, thus retaining the arch-support in position in the shoe.

The bearing plate *g* for the turning pin *b*, as also the sliding plate *d* for the adjusting pin *e* have preferably only one end secured to the cover *c* so that their other ends can easily be raised, and the arch-plate properly inserted, adjusted and again removed when required for exchanging the same. The ends of the arch-plate are thus provided with a firm, secure and flat support on the plates *d* and *h*.

In rendering the heel part of the arch-plate also adjustable on the sole, in addition to the angular adjustment of the ball part, it is of course optional whether the construction is effected as herein described, or whether other suitable means are employed for the purpose.

Having thus described my invention 60 what I claim as new and desire to secure by Letters Patent is:

1. An arch support for footwear comprising an arch-plate having a heel and ball part, a cover-piece for said plate, means for turning and adjusting the heel part at various angles relatively to the longitudinal center line of said cover piece, and means for guiding and allowing the ball part to slide longitudinally. 70

2. An arch support for footwear comprising an arch-plate having a heel and ball part, a cover-piece for said plate, means for turning and adjusting the heel part at various angles relatively to the longitudinal center line of said cover piece, a fixed guide plate having a number of slots arranged radially to the turning center of the heel part, and a pin in the ball part, said pin being adapted to engage with any of the slots 80 in the guide plate.

3. An arch support for footwear comprising an arch-plate, having a heel and ball part, a cover-piece for said plate, means for turning and adjusting the heel part at various angles relatively to the longitudinal center line of said cover piece, a fixed guide permitting of free longitudinal movement of the arch-support, said guide having a number of guide slots arranged radially to 90 the turning center of the heel part, and a pin in the ball part, said pin being adapted to engage with any of the slots so as to allow a sliding movement of the ball and of the arch-support. 95

4. An arch support for footwear comprising an arch-plate, having a heel and a ball part, a fixed plate having a number of holes, a pin on the heel part, said pin being adapted to engage with any of said holes, 100 and means for preventing accidental disengagement of the pin from the hole.

5. An arch support for footwear comprising an arch-plate having a heel and a ball part, fixed plates for supporting the heel and ball parts, said plates being so arranged as to permit of adjustment of the arch-support, and means on said heel and ball parts engaging with the fixed plates, said means being such as to permit a turning movement of the heel part and longitudinal sliding movement of the ball part. 110

In testimony whereof I affix my signature in presence of two witnesses.

JOSEPH MAY.
